HANS J. E. BANCK, OF SPRINGFIELD, ILLINOIS, ASSIGNOR TO SPRINGFIELD BOILER CO.,
OF SPRINGFIELD, ILLINOIS, A CORPORATION OF ILLINOIS

STEAM GENERATOR

Application filed March 10, 1927. Serial No. 174,108.

My present invention relates to steam generators and particularly to steam generators of the type in which a large portion of the heat is absorbed by direct radiation from a combustion chamber in which a high temperature is maintained as by the combustion 5 therein of powdered coal; and the primary object of the present invention is to provide an advantageous disposition of water tubes absorbing radiant heat from the combustion chamber and from the heating gases which leave the combustion chamber while still at a relatively high temperature, and to combine with the water tubes steam collecting provisions and water circulating provisions permitting 10 of the effective use of the water tubes in absorbing heat and generating steam at the very rapid rate at which water tubes are adapted to absorb heat by direct radiation from a combustion chamber in which a high 15 temperature is maintained and by direct contact with heating gases passing over the water tubes at high velocity and at high temperatures.

Water tubes lining the walls of a combustion chamber in which such high temperatures are maintained as are readily possible and desirable and indeed practically inevitable when powdered coal is burned with the aid of preheated combustion air, absorb heat 20 at a rate per square foot of heating surface very greatly in excess of the average rate of heat absorption by the boiler heating surface of an ordinary steam generating boiler 25 in which a substantial portion of the heat utilized is absorbed from the heating gases after the latter have been cooled substantially below the combustion chamber temperature. For example, one of the constructions hereinafter described as a preferred 30 embodiment of the invention is designed and adapted for the absorption of heat at an average rate per square foot of heating surface approximately 20 times the average rate of heat absorption per square foot of boiler heating surface in a water tube boiler operating at normal rating.

My invention is characterized by the provisions made for keeping the water tubes 35 properly filled with water notwithstanding

the rapid generation of steam in the tubes. To this end the water tubes are vertically disposed so far as possible, and provisions are made for normally maintaining a hydraulic head in all portions of the water tubes absorbing heat to any appreciable extent, and in addition provisions are made for a sort of steam and water separating action at the top of each water tube, to permit the ready escape of the steam liberated in the tube while obstructing the discharge of water from the tube. In the practical carrying out of the invention, I provide a steam and water drum or other steam collector at a level well above the uppermost portion of the boiler in which 40 any substantial heat absorption by the water tubes occurs and extend the vertical water tubes or uprising tubes or pipes receiving steam and heated water from the water tubes proper to the level of the steam collector and connect said tubes or pipes to the steam collector well above the water level in the generator in such fashion as to obstruct or restrict the passage into the steam collector of water carried upward in the tubes by the 45 steam to a level above the normal water level of the boiler.

Further specific objects of the invention are to combine with the steam generator proper, simple and effective provisions for 50 utilizing available heat in the gases leaving the generator to preheat the combustion supporting air, and for superheating the steam when, as is usually the case, it is desirable to utilize a portion of the heat generated 55 in the boiler furnace in superheating the steam. Another specific object of the invention is to provide my improved steam generator with effective means for collecting the cinders or furnace dust.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and 95 100

described preferred embodiments of my invention.

Of the drawings:

Fig. 1 is a side elevation with portions 5 of the housing broken away and removed;

Fig. 2 is a sectional elevation taken on the line 2—2 of Fig. 3;

Fig. 2A is an elevation illustrating a modified form of a portion of the apparatus 10 shown in Fig. 2, eliminating box D³;

Fig. 3 is a rear elevation;

Fig. 3A is an enlarged rear view of a portion of the headers and the feed valve partly in section;

15 Fig. 4 is a plan in section on the line 4—4 of Fig. 2;

Fig. 5 is a partial section on the line 5—5 of Fig. 2;

20 Fig. 6 is a partial section on the line 6—6 of Fig. 2;

Fig. 7 is a partial section taken similarly to Fig. 4 but on a larger scale;

Fig. 8 is a partial section on the line 8—8 of Fig. 2;

25 Fig. 9 is a somewhat diagrammatic representation of a steam generator of modified form; and

30 Figs. 10, 11, and 12 are diagrammatic elevations each illustrating a different form of steam generator.

In the form of embodiment of my invention illustrated in Figs. 1 to 6, A represents a combustion chamber shown as rectangular in horizontal cross section, and having an 35 upwardly inclined roof, and a hopper shaped cinder collector O at its bottom. B represents suitably disposed powdered coal inlet or burner nozzles, and C represents distribution boxes shown as running around the 40 combustion chamber for supplying preheated air for combustion to the combustion chamber through ports C' opening into the combustion chamber at suitably distributed points. The front, back, side and roof walls 45 of the combustion chamber A incorporate or are lined by water tubes which form a large portion of the boiler heating surface.

As shown, the combustion chamber front wall water tubes D are vertically disposed 50 and are connected at their lower ends to a horizontal header d. Each tube D is connected at its upper end through a suitable box like connector D' to a roof tube D² shown as connected at its upper end into a vertical box like header D³. The vertically disposed combustion chamber rear wall tubes E are connected at their lower ends to a horizontal header e. Each tube E is connected at its 55 upper end into one of the corresponding box like connectors D³. Each connector D³ is connected to the elevated horizontal steam collecting drum H through vertical tubes D⁴ which are connected at their lower ends to the connectors D³ and are connected at their 60 upper ends into box like connectors D⁵

which are directly connected to the drum H by short horizontal pipes or nipples D⁶.

In the construction shown in Figs. 1 to 6, inclined screen tubes d' extend across the combustion chamber A above the hopper O. 70 The upper ends of the tubes d' are connected to the header d, and the lower ends of the tubes d' which extend between the tubes E, are connected to a header d² adjacent the header e.

The upper portions of the tubes E extend across the outlet A' from the combustion chamber A, for the heating gases, the tubes E being spaced apart to provide a suitable aggregate flow area for the heating gases which 80 pass from the combustion chamber into the convection heated portion of the steam generator which comprises a chamber A² including a bank of vertically disposed water tubes G and G¹², and superheater elements K. As 85 shown, a baffle G¹⁰ causes the heating gases to make a lower and a reverse upper pass in flowing from the combustion chamber outlet A' to the heating gas outlet A³ from the chamber A². The lower of these passes includes the upper ends of the tubes E, and the lower portions of the tubes G and G¹² and of the superheater elements K, while the upper portions of the elements K and of the tubes G' and G and the lower portions of the tubes D⁴ are included in the upper pass 90 through the chamber A². As shown, the tubes G' and G¹² are connected at their lower ends into sectional headers g which are located at the bottom of the chamber A², and are inclined to the horizontal, and receive water at their lower ends through nipples g' from a horizontal header g². At their upper ends the headers g are connected to the lower ends of inclined tubes G² which are in 100 effect extensions of the headers g, and as shown form a screen between the bottom of the chamber A² and the top of a hopper shaped cinder collector O' below the chamber A². At their upper ends the tubes G² are connected through connectors or short headers G³ to the lower ends of corresponding 105 vertically disposed tubes G⁴. The tubes G⁴, which line the rear wall of the chamber A², are connected to short horizontal headers G⁵. At their upper ends the tubes G and G' are connected into inclined sectional headers g³. The headers g³ are connected at their upper ends by tube extensions G⁶ into the headers G⁷. The latter are connected by vertically disposed tubes G⁷, box like connectors G⁸, and short horizontal tubes or nipples G⁹ into the drum H at the opposite side of the latter from that to which the nipples D⁶ are connected. The headers g³ and tubes G⁶ and the heat insulating material X which they 110 support form the roof of the chamber A² which is located a considerable distance below the drum H.

Each side wall of the combustion chamber 115

A is lined or formed in part by a vertically disposed row of tubes F. The various tubes F at each side of the boiler are connected at their lower ends into a corresponding horizontal lower header F' and are connected at their upper ends into a corresponding upper header F². Advantageously, as shown, the headers F² are less acutely inclined to the horizontal than are the tubes D² and cross the latter. This leaves the connector boxes D³ at the sides of the boiler accessible without complicating the housing X at the side edges of the roof of the combustion chamber. Each header F² is connected at its upper end by a bent pipe F³ into the corresponding end of a horizontal drum F⁴ alongside of and at the rear of the drum H. The header F⁴ is connected to the drum H by a series of short horizontal pipes or nipples F⁵. The side walls of the chamber A² are each lined by a row of vertically disposed tubes FA. The tubes FA at each side of the chamber A² are connected at their lower ends to an inclined header FA' alongside the headers g and extensions G² thereof, and at their upper ends the tubes FA in each row are connected to a sectional header FA² alongside the headers g³ and the tube extensions G⁶ thereof. At its lower end each header FA' is connected by a vertical nipple FA⁶ to the water drum or header g². Each header FA² is connected at its upper end by a vertically disposed pipe FA³, box-like connector FA⁴ and horizontal nipple FA⁵ into the drum H. The nipples F⁵ extend between the tubes G⁷, and the header F⁴ is located at the rear of the tubes G⁷.

The headers d², e, F', and g² are supplied with water through down-comer piping external to the boiler housing comprising a vertically disposed pipe I at each rear corner of the boiler. Each pipe I has a lower branch pipe I' connected to the adjacent ends of the headers d² and e, a second branch pipe I² connected to the adjacent end of the corresponding header F', and a branch I³ connected to the adjacent end of the header g². The upper ends of the pipes I may be connected directly into the drum H, but I prefer to connect those pipes into a smaller drum or header h, shown as located directly beneath the drum H and connected to the latter by a row of nipples or short vertical tubes H'. The feed water supply connections J may also be connected into the ends of the drum H but preferably are connected into the ends of the header h. In the form shown, the connection to each end of the headers h of an elbow fitting forming the portion of each pipe I directly connected to the header h, and each branch I⁴ is shaped to provide a water sealed outlet from the feed valve J' through which each pipe J is connected to the corresponding branch I⁴. The water seals thus provided practically eliminate all possibility of water hammer in case the water

level in the boiler falls below the header h, as it may, without any serious consequence.

The header H may advantageously be provided with perforated or slotted baffles H² in front of the nipples D⁶ and G⁹, F⁵, and FA⁵, to minimize water turbulence in the drum H, and to restrict the amount of moisture carried out of the drum with the steam through the header steam outlets H³. To avoid disturbances with fluctuating water levels, a perforated baffle H⁴ is advantageously located in the drum H above the nipples H'. The header H is shown as provided with a multiplicity of outlets H⁵ to which safety valves (not shown) are attached. The steam outlets H³, of which two, one adjacent each end of the header H, are shown, are connected by piping HC to the superheater inlet header K', which, as shown, is located immediately above the roof of the chamber A², and below the superheater outlet header K² which is between the headers K' and h.

L represents a water level gage column connected to the end of the drum H, and a lower water level gage column LA is connected into one of the pipes I.

The boiler as a whole is supported by suspension devices from external structural girders or beams M which may be carried by the boiler house columns (not shown). As shown, the steam collector H is supported by suspension straps M', and each collector box D' is supported by an individual suspension link M²; each junction box D⁵ is supported by two suspension links M²; each of the headers G⁸ is supported by one or more suspension links M², and suspension links are provided for the connection boxes FA⁴ and headers F⁴. The headers F² are also suspended by suitably disposed links M². The superheater headers are shown as supported by straps M³ from the collector H. With the described arrangement, the boiler water tubes and connectors are divided into suitably small sectional units individually suspended so that relative contraction and expansion of the parts of the boiler may occur without subjecting any portion of the structure to objectionable strain. With all portions of the walls of the combustion chamber A and convection heating chamber A² lined by or incorporating water tubes, as described, the boiler housing X can be relatively light in weight and inexpensive, and may be wholly or largely supported by the water tubes and connectors without likelihood of serious heat radiation losses, or of objectionable air or gas leakage into or out of the interior of the boiler. One suitable form of housing X illustrated in Fig. 7, comprises tile X' fitting against the outer sides of the water tubes, and a packing X² of kieselguhr or the like between the tile X and an external metal sheathing.

Portions of the water tubes and connector boxes and headers may be covered by refrac-

tory material where it is desirable to minimize the heat absorption to prevent steam generation which might objectionably interfere with the water circulation, and to protect connector boxes and headers against possible overheating. Thus, as shown, the surface portions of the tubes D^2 exposed to radiant heat from the combustion chamber A are reduced by the use of housing forming tiles X^6 which fit against the major portion of the surfaces of the tubes. The tubes or nipples G^6 and headers G^3 are advantageously completely enclosed by refractory material, and the undersides of the sectional headers g^3 are advantageously covered by tiles, refractory cement or the like. In general, also, all of the connector boxes exposed to high temperatures are covered by tiles or other refractory material, and the portions of the headers F' and F^2 which otherwise would be exposed at the interior of the combustion chamber are covered by refractory material. Advantageously, also, the portion of the boiler structure proper above the chamber A^2 is enclosed by heat insulating material as shown so that the headers h and K' and K^2 are enclosed in a chamber A^4 at opposite sides of which the tubes G^7 and D^4 are located.

The most effective use of the type of steam generator illustrated in Figs. 1 to 6, particularly in generating steam at the high pressures now coming into use, requires that the heating gases should leave the boiler proper through the outlet A^3 , at a temperature which is many hundred degrees above that of the atmosphere. To recover the available heat in the gases leaving the boiler proper any usual or suitable waste heat device as an air preheater or feed water heating economizer, may be employed, and any such device may be located with advantage in the space immediately above the combustion chamber. In burning powdered coal all of the available heat in the gases leaving the boiler proper may advantageously be used in preheating air for combustion, and in the construction shown in Figs. 1 to 6, N represents an air preheater for this purpose.

The air preheater N may be of any suitable type, and as conventionally illustrated, is of the well known plate or flat tube recuperator type, with the air passages in the preheater leading from an air inlet N' to an air outlet N^2 . The heating gases enter the gas passages of the preheater from a chamber N^3 , the bottom wall of which may be formed in large part by the portion of the boiler housing supported by the tubes D^2 , and the heating gases pass away from the air heater to a stack, or, more usually, to a draft inducing fan through the top gas outlet N^4 . The air ordinarily supplied to the preheater inlet N' by a forced draft fan (not shown) passes from the preheater air outlet N^2 through a conduit N^5 located at the front of the boiler and discharges at its lower

end through branches N^6 and N^7 to the air distribution boxes C of which two are shown located one above and the other below the burners B . The amount of preheated air supplied to the combustion chamber above and below the burners B may be suitably regulated as by means of dampers N^8 .

The location of the air preheater above the combustion chamber as shown in Figs. 1 to 6, obviously economizes space and cheapens the cost of construction and improves the operation by simplifying and shortening the air and gas passages. Furthermore, this disposition of the waste heat apparatus is advantageous as portions of the boiler housing are utilized as a part of the air preheater housing, and heat radiated upward from the roof of the combustion chamber, for example, is in large part recovered in the air heater.

In burning powdered coal, particularly in urban power houses, it is highly desirable that the discharge of cinder dust into the atmosphere should be reduced to a practical minimum, and in the operation of any powdered coal burning boiler furnace provisions must be made to avoid cinder accumulations interfering with the operation of the furnace. With the construction shown in Figs. 1 to 6, the cinders are largely eliminated from the gases before the latter reach the preheater outlet N^4 , and the cinders settling out of the gases may be easily disposed of. A large portion of the cinders formed are directly received in the dust collector O , from which they can be removed in any usual or suitable manner. The cinder dust settling out of the gases in the chamber A^2 are largely received in the collector O' . The latter is advantageously provided with a door O^5 for the discharge of the cinders collected, and to permit access to the chamber A^2 and the removal of superheater elements K and adjacent tubes G' when replacements of such elements and tubes are necessary. To permit of ready entrance into the chamber A^2 one or more of the nipples G^2 may be omitted. The omission of some of the nipples G^2 connected to any one header G^3 will not interfere materially with the desired circulation since the remaining nipples will supply all of the water which needs to be supplied to that header. It is obvious that cinders or furnace dust piling up on the headers g may be blown by ordinary soot blowers (not shown) into the combustion chamber A , in which case they enter the cinder collector O or into the collector O' . Cinders accumulating on the baffle G^{10} or connector boxes D^3 may be blown into the chamber A^2 . AD' and AD^2 are access doors adapted for inspection and cinder removing purposes for the collector D^3 and the headers, respectively. Cinders collecting in the chamber N^3 may be discharged from the latter from time to time through clean-out openings normally closed by doors N^9 opening into pip-

ing O¹⁰ which may be arranged, as shown best in Fig. 2, to pass the cinders into the hopper O.

Any usual or suitable disposition of the burner nozzles B and air inlet ports C' may be employed, and I have not thought it necessary to illustrate and describe these features of the construction in detail. In general, however, the nozzles B and ports C' are arranged to open into the combustion chamber in the 10 spaces between the tubes D, E, or F lining the vertical walls of the chamber. Advantageously, with the particular combustion chamber arrangement employed in the construction shown in Figs. 1 to 6, the portion 15 of the air boxes C at the sides of the combustion chamber slope downward from the front to the rear of the combustion chamber.

The general mode of operation contemplated of the apparatus shown in Figs. 1 to 6 20 will be fairly apparent from what has already been said. Fuel and preheated air for combustion are supplied to the combustion chamber, in regular operation, to provide the heat required, and to insure efficient combustion 25 and the maintenance of a suitably high combustion chamber temperature. The major portion of the heat utilized in the generation of steam is radiant heat absorbed directly from the combustion chamber by the tubes 30 D, D', D'', F, and E. The heating gases issuing from the combustion chamber outlet port A' sweep through the chamber A² and give up the remaining portion of the heat recovered in the boiler proper to the water tubes 35 and superheater elements located in the chamber A². The heating gases leaving the boiler proper through the outlet A³ give up their available heat to the air supporting combustion 40 as the air and the heating gases pass through the air preheater N. The heat absorbing surface of the boiler proper is highly effective, and the average rate of heat absorption per square foot of boiler heating surface 45 may well be twenty times that of a boiler operating at normal rating. Such a radical increase in capacity as compared with ordinary boiler practice possesses obvious and important practical advantages. With efficient means as described for recovering available 50 heat from the heating gases leaving the boiler proper, the over-all efficiency of the improved steam generator may be relatively high.

The practical effectiveness of my improved 55 steam generator with the absorption of heat by the boiler heating surface which is not only possible but desirable, depends in large part upon the vertical disposition of the tubes absorbing heat at a rapid rate and on the fact 60 that the water in the portions of the tubes absorbing heat at a rapid rate is under a substantial hydraulic head, and on the fact that the tubes are connected into the circulating system in such manner that the rapid flow of 65 steam through and out of the tubes does not

prevent the portions of the tubes absorbing heat at a rapid rate from being substantially filled with water at all times. The vertical disposition of the heat absorbing tubes is desirable because the frictional resistance to the flow of a turbulent mixture of water and steam is much less in a vertical tube than in a tube sufficiently inclined to the vertical to concentrate the steam in bubbles or bodies in contact with the roof of the tube passage, and a reduction in such frictional resistance facilitates the escape of the steam generated and the inflow of the water replacing that evaporated. This desirable reduction in frictional resistance to flow in vertical tubes tends to an undesirably rapid discharge of water from the tubes. This tendency is minimized in accordance with the present invention in part by the hydraulic head impressed on the water in the portions of the tubes absorbing heat at a rapid rate, and in part by the steam and water separating action, and flow restricting effect of the connections between the upper ends of the tubes and the drum H. The connector boxes D⁵, F⁴, G⁸ and FA⁴ are 70 located above the normal water level and are connected to the drum H by horizontal nipples. 75

The abrupt change in the direction of the flow of water and steam which enters the connector boxes and passing from the latter into the drum H restricts the flow and makes the steam pressure somewhat higher in the connectors than in the drum H. This pressure difference tends to the maintenance of a steam space in the connectors and the upper ends of the tubes connected thereto, and it is to be noted that this tendency is much larger with a heavy boiler load when it is most helpful, than when the boiler load is light. 85 90 95

Further, when water enters the connector boxes it ordinarily enters in waves or recurring jets and with considerable velocity and impinges more or less violently against the top of the walls of the connectors. This tends to separate the steam and water, and to facilitate the return of the water into the tubes, even though the upper ends of the latter are filled with a seething mass of steam and water. From the foregoing, it will be 100 observed that the drums H and h, connector boxes D⁵, F⁴, G⁸ and FA⁴, and nipples D⁶, F⁵, G⁹ and FA⁵ collectively constitute steam and water separating and receiving means. 105 110 115 The fact that but little if any heat is absorbed by the upper portions of the tubes gives time for a natural separation of the steam and water as by the flow of the steam up through the volumes of water in the tubes. A reduction in the amount of water carried into the steam collector H reduces the amount of water unnecessarily moved through the tubes in which steam is generated, and while the restricted discharge into the header H tends of itself to reduce the flow of water 120 125 130

into the lower ends of the tubes, the relatively great elevation of the header H above the lower water headers, and the fact that the down-comer piping I is external to the boiler proper so that the water is cooled rather than heated in passing through this piping insures an ample feed of water to the lower ends of the tubes.

The improved boiler construction is characterized by numerous and more or less readily apparent advantages in construction and arrangement which facilitate inspection, tube replacements and other repair and maintenance operations. The entire boiler may be easily drained, as by means of a suitable blow-off connection to the header e. The water storage capacity of my improved boiler may be relatively small, since appreciable fluctuations in the boiler water level may occur without any appreciable interference in the regular operation of the boiler. While I contemplate that normally the water level of the boiler will be between the steam and water inlets to and below the water outlet from the drum H so as to be indicated by the water gage glass L, the operation of the boiler will be perfectly safe and substantially satisfactory if the water level falls so far that the water level gage column LA is only partly filled with water. This is an indication of the fact that with proper steam and water separating provisions at the tops of the tubes, the drum H need not serve as a steam and water drum, but only as a mere steam collector or header.

It is obvious that many changes in the details of construction illustrated in Figs. 1 to 6 may be made. For example, the connector boxes D² may be omitted, the tubes D² and E' then being extended to the connectors D⁵ as shown in Fig. 2A. It is apparent also that the general advantages of the invention may be obtained with boiler organizations differing materially in general form and appearance from that illustrated in Figs. 1 to 6, and in Figs. 9 to 12 inclusive, I have illustrated in a somewhat diagrammatic manner some of the modifications which may be employed. The boiler shown in Fig. 9 comprises a combustion chamber A⁹ with water tubes DA and EA at its front and rear sides. The water tubes DA are connected at their upper ends by inclined tubes DA' to connection boxes DA², and the tubes EA are connected by oppositely inclined tubes EA' to connection boxes EA². The boxes DA² and EA² are located at the opposite side of the drum H, and are connected to the latter by nipples, as are the boxes D⁵ and G⁸ in the construction first described. The tubes EA' and DA' cross one another, and with the portion of the boiler housing X supported by these tubes form the roof of the combustion chamber A⁹. As shown, there is a bank comprising several rows of tubes EA, and the heat-

ing gases leaving the combustion chamber A⁹ traverse the bank of tubes EA, a bank of vertically disposed superheater elements K, and a second bank of vertically disposed water tubes GB. As shown, the chamber A²⁰ including the tubes EA and GB, and elements K, is not baffled, so that the heating gases make a single horizontal pass over these tubes and elements. As shown, the upper ends of all the tubes EA are connected to the drum H through the headers EA⁴, tubes EA', and boxes EA², while the upper headers GB² for the tubes GB are connected to the drum H by uprising pipes GB³, boxes GB⁴, and horizontal nipples or tubes GB⁵. IA represents the down-comer water piping connecting the drum H to the headers or water drums DA' and EA³ to which the lower ends of the pipes DA and EA are connected. The headers GB' to which the lower ends of the tubes GB are connected receive water through tubes or nipples GB⁶ from the headers EA³. In Fig. 9, the powdered coal burner nozzles BA extend into the top of the combustion chamber through the spaces between the tubes EA' and DA'. I have not thought it necessary to illustrate in Fig. 9 the arrangement for supplying combustion supporting air to the combustion chamber, nor to illustrate the water tubes which would ordinarily be provided to cool the side walls of the combustion chamber A⁹.

In the construction shown in Fig. 10, the combustion chamber A¹⁰ is lined at its front and back sides by tubes DB and EB, intermediate portions of which are inclined to the vertical to conform to the tapering shape of the upper portions of the combustion chamber. The heating gases leaving the combustion chamber A¹⁰ make three passes across a bank of vertically disposed tubes GC located in the convection heating chamber A²¹ of the boiler, G¹¹ and G¹² representing gas deflecting baffles. The heating gases pass from the outlet A²¹⁰ of the chamber A²¹ into an economizer NB and from thence into an air heater NA having a stack outlet connection NA'. The tubes GC are connected at their lower and upper ends to inclined headers GC' and GC² respectively, and as shown, the upper ends of the tubes EB are connected into the upper ends of the headers GC². The upper ends of the latter are connected to the steam and water drum H through connector boxes GC⁴ and GC⁶ at the opposite sides of the drum H and tubes GC³ and GC⁵. The upper ends of the tubes DB are connected into the connectors GC⁴. IB represents the down-comer piping supplying water passes from the feed water header h to the water drum EB' beneath the tubes EB and directly connected to the latter, and connected to the lower ends of the tubes DB through screen tubes DB'. The piping IB also supplies water to the tubes GC. O¹⁰

represents a cinder collector at the bottom of the chamber A, O' a cinder collector at the bottom of the chamber A¹², and O¹² a cinder collector at the bottom of the economizer NB.

5 In Fig. 11 I have shown a double ended boiler each section of which comprises a combustion chamber A¹⁰ and a chamber A²¹⁰ and associated tubes and piping practically identical with the corresponding parts of the boiler shown in Fig. 10 except for the omission of the screen tubes and the consequent changes in the form of the water supply piping. In Fig. 11 also the connector boxes GC⁶ and tubes GC⁵ are omitted, the connector boxes GC⁴ for the two sections of the boiler being at opposite sides of the common drum H. In Fig. 11 the two chambers A²¹⁰ which are placed back to back are separated to provide space for a waste heat device NC receiving heating gases from both chambers A²¹⁰. The device NC may be an economizer, an air preheater, or may comprise separate economizer and air preheater sections. The boiler shown in Fig. 11 is practically identical with 25 the boiler shown in Fig. 10, and need not be further described.

The capacity of the apparatus illustrated for operation at high ratings and with high combustion chamber temperatures, and the comparative ease with which cinders and furnace dust may be collected and disposed of make the invention of especial importance for use with powdered coal firing. It will be apparent, however, that the apparatus hereinbefore described is well adapted for use, practically without change, with oil or gas firing; and the general principles of the invention may be used with advantage in steam generators heated by the combustion of a 40 solid fuel bed, and in Fig. 11 I have shown stoker mechanisms Q for feeding coal onto a fuel bed supported by stoker grates Q' at the bottom of the combustion chamber A¹⁰.

In the relatively simple and compact form 45 of the invention shown in Fig. 12, the tubes DC at the front side of the combustion chamber A¹² extend upward above the combustion chamber to the level of the elevated drum H, to which they are connected, connector boxes DC' and horizontal nipples between said boxes and the drum H. The vertical tubes EC at the rear of the combustion chamber are connected at their upper ends by junction boxes EC' to the tubes EC² which line the 50 roof of the combustion chamber A¹⁴. The tubes EC² have vertical upper portions which extend alongside the upper portions of the tubes DC² and are connected at their upper end to the boxes EC'. The convection heating chamber A²¹² in this form of the invention has its top and bottom walls in alignment, so to speak, with the inclined top and bottom walls of the combustion chamber A¹². 55 The lower portions of the chambers A¹² and

A²¹² are in communication through the spaces between the tubes EC below an inclined baffle G¹⁸ which causes the heating gases to make two passes across the vertical bank of tubes GE in the chamber A²¹². The upper ends of the tubes GE are connected to headers GE', and the latter are connected to the connection boxes EC' through tubes or nipples GE². The heating gas outlet A²¹³ from the chamber A²¹² opens through the roof of the chamber, the escaping gases traversing the tubes GE². A row of tubes GE line the rear wall of the chamber A²¹². The tubes FC lining the side walls of the combustion chamber A¹² and the convection heating chamber A²¹² are connected at their upper ends into inclined headers FC'. The latter are connected by bent pipe portions FC² into headers FC³ at the opposite side of the drum H from the connection boxes DC', and connected to the drum H by horizontal nipples. Down-comer piping IC from the feed water heater drum h is connected by suitable branches into the lower headers to which the tubes FC, EC, and GE are respectively connected. The headers EC³ to which the lower ends of the tubes EC are connected, supply water to the tubes DC through the screen tubes DC² extending across the bottom of the combustion chamber A¹². 70 75 80 85 90 95 100 105 110 115 120 125 130

While in accordance with the provisions of the statutes, I have illustrated and described the best forms of embodiment of my invention now known to me, it will be apparent to those skilled in the art that changes may be made in the forms of the apparatus disclosed without departing from the spirit of my invention as set forth in the appended claims, and that in some cases certain features of my invention may be used to advantage without a corresponding use of other features.

Having now described my invention what I claim as new and desire to secure by Letters Patent is:

1. In a steam generator adapted for operation at ratings greatly in excess of its nominal rating, the combination with vertically disposed water tubes arranged to absorb radiant heat from the combustion chamber of the generator in amount sufficient to generate the major portion of the steam generated, steam and water separating means located at a level substantially above the heat absorbing portions of said tubes including a steam receiving means and conduit connections between the last mentioned means and said tubes arranged to restrict the escape of steam and water into said receiving means from said water tubes and to return to the upper ends of the latter much of the water entering said connections from said tubes, and separate water return connections extending from said receiving means to the lower ends of said tubes and located out of heat absorbing relation with said chamber whereby said heat absorbing tube 130

portions are normally filled with water under an appreciable hydraulic head.

2. In a steam generator adapted for operation at ratings greatly in excess of its nominal rating, the combination with a combustion chamber having vertical side walls and an inclined roof portion, means for burning fuel at high temperatures in said combustion chamber, a multiplicity of radiant heat absorbing water tubes lining the walls and roof of said combustion chamber, substantially all of said wall tubes being vertically arranged, a steam and water drum positioned at a level substantially above and separated from said combustion chamber, vertically arranged tubular connections extending upwardly from the upper ends of said radiant heat absorbing water tubes, and conduit elements connecting the upper ends of said tubular connections to said drum and arranged to prevent an undesirably rapid discharge of water from said tubular connections into said drum.

3. In a steam generator adapted for operation at ratings greatly in excess of its nominal rating, the combination with a combustion chamber enclosed by vertical walls and an inclined roof, means for burning fuel at high temperatures in said combustion chamber, a multiplicity of radiant heat absorbing water tubes lining the vertical walls and roof of said combustion chamber, substantially all of said wall water tubes being vertically arranged, a horizontal steam and water drum positioned substantially above and separated from said combustion chamber and arranged out of contact with said heating gases, vertical tubular elements extending upwardly from the upper ends of said water tubes in said combustion chamber, and means connecting said tubular elements to said steam and water drum preventing an undesirably rapid discharge of water from said tubular elements into said steam and water drum, said means comprising horizontal conduits connected to said drum above the water level therein and chambered members of greater internal cross section than said elements and conduits connecting the latter to said elements.

4. In a steam generator adapted for operation at ratings greatly in excess of its nominal rating, the combination with a combustion chamber enclosed by vertical walls, means for burning fuel at high temperatures in said combustion chamber, a multiplicity of radiant heat absorbing water tubes lining the vertical walls of said combustion chamber, substantially all of said water tubes being vertically arranged, a second chamber laterally disposed relative to said combustion chamber, and connected thereto for the passage of heating gases at high temperatures therebetween, a multiplicity of water tubes in said second chamber arranged in the path of flow of said heating gases, substantially all of said last mentioned tubes being vertically ar-

ranged, a horizontal steam and water drum positioned substantially above and separated from said second chamber and arranged out of contact with said heating gases, vertical tubular elements extending upwardly from the upper ends of said water tubes in said combustion and second chambers, and conduit means connecting said tubular elements to said steam and water drum and arranged to prevent an undesirably rapid discharge of water from said tubular elements into said steam and water drum.

5. In a steam generator adapted for operation at ratings greatly in excess of its nominal rating, the combination with a combustion chamber enclosed by vertical walls, means for burning fuel at high temperatures in said combustion chamber, a multiplicity of radiant heat absorbing water tubes lining the vertical walls of said combustion chamber, substantially all of said water tubes being vertically arranged, a second chamber laterally disposed relative to said combustion chamber, and connected thereto for the passage of heating gases at high temperatures therebetween, a multiplicity of water tubes in said second chamber arranged in the path of flow of said heating gases, substantially all of said last mentioned tubes being vertically arranged, a horizontal steam and water drum positioned substantially above and separated from said second chamber and arranged out of contact with said heating gases, vertical tubular elements extending upwardly from the upper ends of said water tubes in said combustion and second chambers, means connecting said tubular elements to said steam and water drum and horizontally arranged to prevent an undesirably rapid discharge of water from said tubular elements into said steam and water drum, and external pipe connections from said steam and water drum to the lower ends of said water tubes.

6. In a steam generator adapted for operation at ratings greatly in excess of its nominal rating, the combination with a combustion chamber enclosed by vertical walls, means for burning fuel at high temperatures in said combustion chamber, a multiplicity of radiant heat absorbing water tubes lining the vertical walls of said combustion chamber, substantially all of said water tubes being vertically arranged, a second chamber laterally disposed relative to said combustion chamber, and connected thereto for the passage of heating gases at high temperatures therebetween, a multiplicity of water tubes in said second chamber arranged in the path of flow of said heating gases, substantially all of said last mentioned tubes being vertically arranged, a horizontal steam and water drum positioned substantially above and separated from said second chamber and arranged out of contact with said heating gases, vertical

tubular elements extending upwardly from the upper ends of said water tubes in said combustion and second chambers, a plurality of connector boxes connected to the upper ends of said vertical tubular elements, and conduits connecting said connector boxes to said steam and water drum.

7. In a steam generator adapted for operation at ratings greatly in excess of its nominal rating, the combination with a combustion chamber enclosed by vertical walls, means for burning fuel at high temperatures in said combustion chamber, a multiplicity of radiant heat absorbing water tubes lining the vertical walls of said combustion chamber, substantially all of said water tubes being vertically arranged, a second chamber laterally disposed relative to said combustion chamber, and connected thereto for the passage of heating gases at high temperatures therebetween, a multiplicity of water tubes in said second chamber arranged in the path of flow of said heating gases, substantially all of said last mentioned tubes being vertically arranged, a horizontal steam and water drum positioned substantially above and separated from said second chamber and arranged out of contact with said heating gases, vertical tubular elements extending upwardly from the upper ends of said water tubes in said combustion and second chambers, a plurality of separate connector boxes connected to the upper ends of said vertical tubular elements, and horizontal tubular conduits separately connecting said connector boxes to said steam and water drum above the normal water level in said drum.

8. In a steam generator adapted for operation at ratings greatly in excess of its nominal rating, the combination with a combustion chamber enclosed by vertical walls, means for burning fuel at high temperatures in said combustion chamber, a multiplicity of radiant heat absorbing water tubes in said combustion chamber, a second chamber laterally disposed relative to said combustion chamber and connected thereto for the passage of heating gases at high temperatures therebetween, a multiplicity of water tubes in said second chamber arranged in the path of flow of said heating gases, a steam and water drum positioned at a level substantially above and separated from said combustion and second chambers, tubular connections between said water tubes and said drum, said connections being arranged to prevent an undesirably rapid discharge of water from said water tubes into said drum, a feed water supply connection to said drum, an external downcomer pipe connecting said supply connection to the lower ends of said water tubes, and a water seal incorporated in said supply connection.

9. In a steam generator adapted for operation at ratings greatly in excess of its nomi-

nal rating, the combination with a combustion chamber enclosed by vertical walls, means for burning fuel at high temperatures in said combustion chamber, a multiplicity of radiant heat absorbing water tubes in said combustion chamber; a second chamber laterally disposed relative to said combustion chamber and connected thereto for the passage of heating gases at high temperatures therebetween, a multiplicity of water tubes in said second chamber arranged in the path of flow of said heating gases, a steam and water drum positioned at a level substantially above and separated from said combustion and second chambers, tubular connections between said water tubes and said drum and arranged to prevent an undesirably rapid discharge of water from said water tubes into said drum, a plurality of superheater tube elements vertically arranged in said second chamber in the path of flow of said heating gases, and means connecting said superheater elements to said steam and water drum.

10. In a steam generator adapted for operation at ratings greatly in excess of its nominal rating, the combination with a combustion chamber having vertical side walls and an inclined roof portion, of means for burning fuel in suspension at high temperatures in said combustion chamber, means for supplying preheated air to spaced points in said combustion chamber, a multiplicity of radiant heat absorbing water tubes lining the walls and roof of said combustion chamber, a second chamber laterally disposed relative to said combustion chamber and connected thereto for the passage of heating gases at high temperatures therebetween, a multiplicity of vertically arranged water tubes in said second chamber, a horizontal baffle in said second chamber providing a serial flow of heating gases over the lower and upper portions of said water tubes, a steam and water drum positioned substantially above and separated from said second chamber, tubular circulation elements separately connecting said steam and water drum to the upper and lower ends of said water tubes, a third chamber above said combustion chamber and laterally disposed relative to said steam and water drum and said second chamber and connected to the latter for the passage of heating gases therefrom, an air preheater located in said third chamber, and a conduit connecting said preheater to said preheated air supply means.

11. In a steam generator adapted for operation at ratings greatly in excess of its nominal rating, the combination with a combustion chamber having vertical side walls and an inclined roof portion, of means for burning fuel in suspension at high temperatures in said combustion chamber, a multiplicity of radiant heat absorbing water tubes lining

the walls and roof of said combustion chamber, a second chamber laterally disposed relative to said combustion chamber and connected thereto for the passage of heating gases at high temperatures therebetween, a multiplicity of vertically arranged water tubes in said second chamber, baffle means in said second chamber providing a serial flow of heating gases over the lower and upper portions of said water tubes, a steam and water drum positioned substantially above and separated from said second chamber, tubular circulation elements separately connecting said steam and water drum to the upper and lower ends of said water tubes, a third chamber above said combustion chamber and laterally disposed relative to said second chamber and connected to the latter for the passage of heating gases therefrom, a heat exchange device located in said third chamber, dust collectors located in the lower ends of said combustion chamber and third chamber, and a conduit means connecting said dust collectors.

Signed at Springfield, in the county of Sangamon, and State of Illinois, this 5th day of March, A. D. 1927.

HANS J. E. BANCK.
